CLAIM

We claim the ornamental design for a pair of athletic shoes, as shown and described.

DESCRIPTION

FIG. 1 is a top view of the right member of a pair of shoes, showing our new design;

FIG. 2 is a lateral side view thereof;

FIG. 3 is a medial side view thereof;

FIG. 4 is a rear view thereof; and,

FIG. 5 is a bottom view of thereof.

The top, lateral side, medial side, rear and bottom views of the left member of the pair of athletic shoes are mirror images of FIGS. 1-5.

The tread on the sole is designed to spell “Under My Feet”.
